UNITED STATES PATENT OFFICE.

MARK SHOELD, OF CHICAGO, ILLINOIS, ASSIGNOR TO ARMOUR FERTILIZER WORKS, OF CHICAGO, ILLINOIS, A CORPORATION OF NEW JERSEY.

ELECTRODE.

1,313,125.

Specification of Letters Patent.

Patented Aug. 12, 1919.

Application filed October 21, 1918. Serial No. 258,941.

To all whom it may concern:

Be it known that I, MARK SHOELD, a subject of the King of Sweden, residing at Chicago, in the county of Cook and State 5 of Illinois, have invented certain new and useful Improvements in Electrodes, of which the following is a specification.

In electric furnaces employing graphite or other comparatively fragile or frangible 10 electrodes trouble is likely to be encountered by their breaking, because of the excessive or unequal strains and stresses to which they are subjected, not only by reason of the heat to which they are submitted, but also be- 15 cause of the uneven settling of the adjacent or associated furnace parts, such, for example, as the heat-resisting or refractory lining.

The leading purpose or prime object of 20 this invention is to overcome these difficulties in a simple, economical, and efficient manner, and, to this end, in the preferred embodiment of the invention the electrode is made of a plurality of electrically-con- 25 ductive parts, desirably slabs or blocks, ar- ranged in superposed horizontal rows rest- 30 ing on one another with the joints offset, so that the members of each row are in over- lapped or interlocked relation with those of the companion rows. To render such a sec- 35 tional electrode efficiently electrically con- ductive it is necessary, or at least desirable, to press these elements together to bring them into relatively good conductive relation with one another and thus in some degree 40 overcome or offset the disadvantages of making the electrode in parts. This is accom- plished or brought about by causing the refractory lining, or a part of it above the 45 electrode, to rest thereon whereby its weight presses the members of the electrode to- 50 gether into comparatively efficient contact. To facilitate this result the lining bricks are not offset or interlocked and hence sub- 55 mit the sectional electrode to a compara- tively uniform pressure, at the same time possessing the capability of settling un- 60 evenly.

This preferred embodiment of the inven- 50 tion is illustrated in the accompanying drawing forming a part of this specification and throughout the views of which like refer- ence characters refer to the same parts.

In this drawing:

55 Figure 1 is a fragmentary, vertical section

through a portion of an electric-furnace equipped with one of the improved elec- 60 trodes; and

Fig. 2 is a horizontal section on line 2—2 of Fig. 1. 60

By reference to the figures of this draw- 65 ing, it will be observed that the sectional or sub-divided electrode comprises a plurality of horizontal rows 10, 11, 12, 13 and 14 of graphite or similar suitable blocks or bars 15 disposed in interlocked or offset relation (see Fig. 2), whereby the blocks of the rows are overlapped in an effective manner, each horizontal stratum or layer comprising a 70 number of such blocks or bars set up in similar manner in transversely overlapped arrangement as indicated in Fig. 1. These conductive members also partially incase or inclose a water-cooled electric-terminal 16 located partly outside of the furnace-shell 75 17 and projecting inwardly a substantial amount to make effective contact with the electrode-blocks which, as is fully shown, are disposed on all sides of it.

The lining or refractory bricks 18 beneath 80 the sectional electrode and which form the support for the latter may be set up or arranged in any convenient way, in inter-locked or overlapped relation if desired; but the lining bricks 19 above, and which rest 85 on, this electrode are desirably disposed in independent vertical rows not interlocked, whereby they may more uniformly and evenly distribute their weight over the up- 90 per surface of the electrode and may if oc- casion requires settle independently of one another. In this simple way the companion elements of the electrode are maintained pressed together and into proper contact 95 with the associated metal terminal. 95

At each side of the electrode a narrow space 20 may be provided and if preferred may be filled with dust or any suitable sub- 100 stance which will not interfere with the pressing of the electrode blocks together.

It will be understood that since the sec- 105 tional electrode is composed of a number of parts each free to shift or move relatively to the others, the electrode as a whole may become distorted somewhat without objec- tional breakage. In other words, the elec- trode can come and go, shift, warp, twist, settle unevenly, and expand and contract without serious detrimental results.

The invention obviously is not limited and 110

restricted to the precise and exact features of construction presented because these may be changed in many respects and still incorporate the principles of the invention and 5 maintain its various benefits and advantages. Accordingly, it is to be understood that the structure shown and described is merely one of several embodiments which the invention may take in commercial and 10 practical shape.

I claim:

1. In an electric-furnace, the combination of an electrode comprising a plurality of superposed overlapping electrically-conductive members and a furnace-lining structure resting and imposing its weight on said members pressing them together, substantially as described. 15

2. In an electric furnace, the combination 20 of an electrode comprising a plurality of superposed overlapping electrically-conductive members and a furnace-lining structure composed of independent vertical sections resting and imposing their weight on 25 said electrode members pressing them together, substantially as described.

3. In an electric furnace, the combination 30 of an electrode comprising a plurality of superposed rows of electrically-conductive members, the members of each row being offset with relation to and overlapping those of the next rows, the members of each row being laterally offset with relation to and overlapping the adjacent members of the 35 same row, and a furnace-lining structure resting and imposing its weight on said electrode members pressing them together, substantially as described.

4. In an electric furnace, the combination 40 of an electric terminal, an electrode comprising a plurality of superposed overlapping electrically-conductive members, and

means to press said members together and at least a portion of them and said terminal, substantially as described. 45

5. In an electric furnace, the combination of a sectional electrode comprising a plurality of superposed overlapping electrically-conductive members, an electric terminal at least partially embedded in said electrode, and a furnace-lining structure resting and imposing its weight on said electrode pressing together its members and at least a part of them and said terminal, substantially as described. 50

6. In an electric furnace, the combination of a sectional electrode comprising a plurality of superposed rows of electrically-conductive members, the members of each row being offset with relation to and overlapping 60 those of the next rows, the members of each row being laterally offset with relation to and overlapping the adjacent members of the same row, an electric terminal at least partially embedded in said electrode, and 65 a furnace-lining structure resting and imposing its weight on said electrode pressing together its members and at least a part of them and said terminal, substantially as described. 70

7. In an electric furnace, the combination of a sectional electrode comprising a plurality of superposed rows of electrically-conductive members, the members of each row being offset with relation to and overlapping 75 those of the next rows, the members of each row being laterally offset with relation to and overlapping the adjacent members of the same row, an electric terminal at least partially embedded in said electrode, and 80 means to press together the members of said electrode and at least a part of them and said terminal, substantially as described.

MARK SHOELD.
